CHRISTIAN HOYER, OF NEW YORK, N. Y., ASSIGNOR TO SHIP BUILDERS IRON WORKS,
INCORPORATED, OF NEW YORK, N. Y., A CORPORATION OF NEW YORK.

DAVIT.

1,274,550.

Specification of Letters Patent.

Patented Aug. 6, 1918.

Application filed March 18, 1918. Serial No. 222,983.

To all whom it may concern:

Be it known that I, CHRISTIAN HOYER, a subject of the King of Denmark, and a resident of borough of Queens, New York city, in the county of New York and State of New York, have invented certain new and useful Improvements in Davits, of which the following is a specification.

This invention relates to improvements in davits.

Especially the invention relates to davits which are pivoted to swing outward so far as to permit a boat to be lowered freely to the water, and on even keel without striking 15 against the side of the ship even when the ship is held down to the side opposite to that on which the life boat is being lowered.

The davits are also constructed and arranged so that the man who is operating 20 each davit shall have an unobstructed view of the davit in all its positions, so as to immediately discern the need of any further movement or cessation of the movement of the davit, without having his view obstructed by any parts of the davit structure 25 or life boat.

And the invention also aims to provide such a construction as shall increase the strength of the davit and the secure holding 30 of the boat in the desired position while being launched. To this end, the davits are constructed so that the strains of the weights of the life boat and the load of passengers, which amount to several tons, are distributed 35 to at least three points not in line with each other, whereby there is no great crushing strain on any one point. The davits are also so constructed that the gears are protected from the weather by suitable housing, 40 and that the davits shall not be weakened by slots or grooves for connecting with the arm by which the davits are operated.

One of the chief advantages of my construction is also that the davit can swing 45 inboard as far as it can swing outboard, and this enables the davit to pick up several boats. If for example there are many boats on the ship so that they require to be arranged on the boat deck, in more rows than 50 one, my davit is so constructed that it can move inboard as far as it can move outboard, and it is therefore able to pick up

any one of the several rows of life boats from the chocks and swing that boat outward over the side of the ship. This ability 55 of my davit to handle several lines or rows of life boats is believed to be new and not possessed by any other davit; it is a very valuable feature of my construction since it enables me to reduce the number of davits 60 on the ship and yet operate the large number of life boats necessary. This is a very desirable feature in the equipment of ships, since the davits are always in the way and are obstructions to the loading and unloading 65 of the vessel, and it is therefore desirable to diminish the number of davits as much as possible. But, on the other hand, there must be davits enough to handle all the life-boats, and the number of life-boats 70 must therefore be great. Consequently by the ability of my davit to swing freely inboard and outboard, so that a single pair of davits can handle a number of rows of boats, I accomplish the important result of adequately launching the life boats, and yet doing 75 so with a much smaller number of davits than is now required.

Referring to the drawings which accompany the specification to aid the description, 80 Figure 1 is a front elevation showing a davit about at its extreme outward position. Fig. 2 in a side elevation, and Fig. 3 is a plan of the same.

It will of course be understood that there 85 will be two similar davits, one for each end of the boat, and I prefer that each davit shall be separately and independently operated by a man or men stationed at that davit. I indeed prefer that the proper operation of the two davits, so as to lower both ends of the life boat on even keel, which is indispensable to the safe lowering of the loaded boat, shall be accomplished by the 90 two men, or two groups of men, one at each davit, and clearly observing the motion of the boat as it is being lowered, to any so-called automatic operation of the two davits in unison with each other; although, of course the features of this invention might 100 be used with davits so connected together that both would be automatically operated together.

But now assuming that there are two

similarly constructed davits, one for each end of the life boat, one davit only being illustrated, A is the davit, which is curved about as shown in Fig. 2, so that the boat, 5 not shown, will hang freely in its chocks. Said davit A is hinged at its lower end on a stout pin, or bolt, a, firmly secured in a bracket b of the frame B, which supports the davit operating gear wheel C.

10 Said davit A is thus hinged at a point not at the center of the said gear C; and consequently the arm or plate D, which connects said davit A with said gear C, must have a motion lengthwise of said davit as said davit moves to and fro; and to insure the possibility of such movement, without resorting to any slots or grooves in said davit, by which the strength of the davit would be much diminished, I provide a box E, or cross-head, 15 which incloses, or practically incloses a part of the said davit. Said davit A, or so much thereof as is sufficient to allow of the necessary travel of said box as the same moves to and fro, is made with parallel sides, so that said box E has a true fit at every part thereof. Said arm D is securely fastened by bolts or rivets to said gear wheel C; which 20 may be only a part or segment of a complete wheel; and said box E is pivotally connected with said arm D by a stud f, which passes through a suitable hole in arm D and is headed on the inside of said arm D. (See Fig. 2.) I may also employ friction rolls to 25 diminish the friction of said box E, as it plays to and fro on the said davit A.

The position of said frame B is such that the plane of the frame is a right angle to the length of the ship, and to the end of the boat both as it swings from the davit and 40 is normally supported in its chocks. The plane, therefore, of the gear C is also perpendicular to the length of the ship or life-boat in its normal position, and this is also the plane of the length of the worm H, which 45 engages said gear C. Finally, the axle of the bevel gear J, which engages the bevel gear I of said worm H, is perpendicular to said frame B, and the crank K, which is operated by the man at the davit is placed 50 near that end of the said frame B which is not obstructed by the davit, or by the boat hanging therefrom; and so that the man can have a clear unobstructed view of the boat in all its positions, and can clearly see and 55 decide upon what further movement of his davit mechanism shall be given to properly lower the boat on an even keel. This I consider one of the most useful of my improvements.

60 Said worm H will of course be supported in suitable bearings on said frame B, and the bearings of said bevel gear J and its axle, as well as said crank, will be supported on a bracket M secured to said frame B.

65 In order to protect the said gear C from

the weather, I provide a housing N for said gear C, bolted to said frame and interrupted where the worm H meshes with said gear C. I may also, if desired, provide a cover for 70 said worm H, and said gears I and J.

It will be seen from the description hereinbefore given, that my davit is supported at at least three points as it moves to and fro, namely, from the pivot a, second, at the connection of the box E, with said davit A, or 75 of the stud of said box E with the arm D, and third, the connection of the worm H with the gear C. The only position in which the davit has not the said three points of support, is that when it is exactly vertical; 80 and then there is no tendency to break or strain the said davit. But in every other position the said davit will have the three points of support.

Now having described my improvements 85 I claim as my invention—

1. In a davit operating mechanism, the combination of a ship's davit adapted to swing inboard and outboard and pivoted to a stationary base, and mechanism for swinging said davit characterized by a worm wheel and means to rotate said worm wheel and an arm on said worm wheel movably engaging a sliding member on said davit. 90

2. The combination of a davit adapted to swing inboard and outboard, a davit operating worm gear and means to rotate said worm gear, an arm on said worm gear and a box adapted to slide on said davit and engaged by said arm. 95

3. In a davit apparatus, the combination of a davit, a worm gear for operating said davit, and said davit being pivoted eccentrically with respect to the center of said worm gear, an arm on said worm gear, a slide- 105 able piece from said davit to said arm and connected with said arm eccentrically to the center of said worm gear, and means for operating said worm gear eccentrically connected with said worm gear. 110

4. In davit operating mechanism, the combination of a davit hinged at its lower end to swing outboard, a box longitudinally movable on said davit, a davit actuating gear wheel and a pivotal connection of said gear wheel with said box, and means operated by a davit operator for actuating said davit gear wheel. 115

5. In davit operating mechanism, the combination of a davit adapted to swing inboard and outboard so far that said davit can pick up an inner boat and swing the same clear outboard to be lowered, a worm gear adapted to operate said davit throughout said swinging motion, an arm on said worm gear, and a box adapted to slide on said davit and engaging said arm. 125

6. In davit operating mechanism, the combination of a davit adapted to swing inboard and outboard so far that said davit 130

can pick up an inner boat and swing the same clear outboard to be lowered, a worm gear adapted to operate said davit throughout said swinging motion, an arm on said 5 worm gear, and a box adapted to slide on said davit and engaging said arm, and housing to protect said gear from the weather.

Signed at New York city, in the county of New York, and State of New York, this 14th day of March, A. D. 1918.

CHRISTIAN HOYER.
